J. W. DAVIS

SAFETY HOLDER FOR MINE SQUIBS AND DETONATORS

Filed Feb. 10, 1922

UNITED STATES PATENT OFFICE.

JOSEPH W. DAVIS, OF ANSTED, WEST VIRGINIA.

SAFETY HOLDER FOR MINE SQUIBS AND DETONATORS.

Application filed February 10, 1922. Serial No. 535,644.

To all whom it may concern:

Be it known that I, JOSEPH W. DAVIS, a citizen of the United States, residing at Ansted, in the county of Fayette and State of West Virginia, have invented a new and useful Safety Holder for Mine Squibs and Detonators, of which the following is a specification.

This invention relates to a safety holder for mine squibs and detonators, one of the objects of the invention being to provide a holder in which explosives of the kind mentioned can be carried safely and in quantities without danger of being prematurely exploded by electric currents in the mines or danger of becoming moist and thus rendered inefficient and dangerous to handle.

It is the practice among miners generally to carry detonators and squibs loosely in the pocket, they sometimes being wrapped in paper so as to protect them to a certain extent from moisture. This practice is extremely dangerous, however, because the explosives are readily discharged by electric currents such as found in mines and the explosives are also likely to become moist so as to cause misfiring and often serious accidents.

It is an object of the present invention to provide a holder which will insulate the explosives therein so that they cannot be exploded by electric currents, the holder also serving to keep moisture away from the explosives.

A further object is to provide a holder in which a number of squibs and detonators can be placed and safely carried.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a plan view of the holder, the same being shown open.

Figure 2 is a section on line 2—2, Figure 1, the holder being closed.

Figure 3 is a section on line 3—3, Figure 2.

Referring to the figures by characters of reference 1 designates the base and 2 designates the lid or cover of the holder. These parts are preferably substantially duplicates of each other, one of them being provided near its edges with a continuous groove 3 while the other is provided near its edges with a continuous rib 4 so that when the cover is in position on the base or body the groove 3 will receive the rib 4 and thus seal the holder. Obviously the cover is connected to the holder preferably by hinges as shown at 5.

Formed within the base or body 1 is a longitudinal recess 6 for holding squibs, this recess extending partly across the base from front to back thereof. In the space between the recess 6 and the front edge of the base is provided a longitudinal series of parallel recesses 7 each designed to hold a detonator. Any number of these recesses may be provided. Correspondingly arranged recesses 8 and 9 are formed in the cover 2 so that when the cover is closed the recess 8 will register with the recess 6 and the recesses 9 will register with the corresponding recesses 7.

The base 1 and the cover 2 are preferably formed of hard rubber or any other suitable insulating material. A spring catch 10 can be secured to the cover 2 and may engage a lug 11 on the base so as to hold the cover in closed position.

By providing a holder such as described explosives of the kind mentioned can be handled safely, there being no danger of premature discharge thereof due to contact with charged electric wires. Furthermore the explosives are protected from moisture.

What is claimed is:

A holder for squibs and detonators, comprising a base member and a cover member of insulating material movably connected, there being a longitudinal recess and a longitudinal series of transverse recesses in each member, the recesses in one member being adapted to register with the corresponding recesses in the other member when said members are closed together, thereby to form a longitudinal squib receiving space and a longitudinal series of transversely extending detonator receiving spaces, all of said spaces being out

of communication with each other, one of the members having a continuous groove in one face thereof adjacent the edges of the face, and a continuous rib on one face of the other member adapted to be seated within the groove to seal the holder when closed.

In testimony that I claim the foregoing as

my own, I have hereto affixed my signature in the presence of two witnesses.

JOSEPH W. DAVIS.

Witnesses:

J. P. WRIGHT,
JOHN R. VAWTER.
